UNITED STATES PATENT OFFICE.

CHARLES FISHER AND GEORGE B. BURNET, OF MANITOWOC, WISCONSIN.

HINGE.

SPECIFICATION forming part of Letters Patent No. 374,954, dated December 20, 1887.

Application filed April 28, 1887. Serial No. 236,472. (No model.)

To all whom it may concern:

Be it known that we, CHARLES FISHER and GEORGE B. BURNET, of Manitowoc, in the county of Manitowoc and State of Wisconsin, have invented certain new and useful Improvements in Hinges; and we do hereby declare the following to be a full, clear, and exact description of the invention, such as will enable others skilled in the art to which it pertains to make and use the same.

Our invention relates to hinges, the object being to provide a hinge of novel and improved construction, especially adapted for piano-lids.

In the accompanying drawings, forming a part of this description, Figures 1, 2, and 3 are cross-section views (on *a a*, Fig. 5) of a piano-lid and our improved hinge secured thereto. Fig. 4 is a detail view of the hinge, and Fig. 5 is a top view of the piano-lid with our improved hinge fitted thereto.

Like letters in the different figures refer to the same parts.

A is the larger lid-section of the piano, and B is the smaller lid, or the one which covers the key-board.

Our hinge consists of two counterpart plates or leaves, C D, each being provided with screw-holes, which serve as a means of attachment to the piano-lids, the hinge being mortised equally into each of the lids A B, as shown. The upper edge of the plate C is provided with two curved wings, C', at right angles with the plate C. The curved wings C' are provided with elongated slots H, as shown.

The upper edge of the plate D is provided with three curved wings, D', similar to C', just described. The curved wings D' are also provided with elongated slots H. The curved wings C' and D' are in such positions on their plates that they will fit within each other or interlock, as shown in Fig. 4, forming a trough which approximates a semicircle in cross-section, and the imaginary center of which is slightly above the surface of the lids A B, as indicated by a dot.

E is a coupling-rod for the two hinged sections. In form this rod is less than a semi-cylinder, and it fits into the trough formed as above described. The curved part of this rod E is provided with threaded holes G in the positions shown.

F is a round head-screw, the portion imme-

dately under its head being enlarged to form a collar, M, adapted to slide within the slot H. This collar M of the screw F is just a trifle longer than the thickness of the curved wings C' D'. The portion n of the screw is of less diameter than the collar M, and forms, in connection with the collar, a shoulder, M'. The portion n is threaded to fit the threaded holes G of the section E. When the coupling-rod E rests within the trough, as above referred to, the threaded holes G are opposite the slots H of the curved wings. The hinge is then put together by passing screws F through the slots H and screwing them securely into the rod E, the shoulder M' of the screw F raising the head of the screw sufficiently to allow the free play of the curved wings C' D' about the rod E. It is evident, however, that the rotative play of the curved wings about the curved portion of the rod E will be limited to the length of the slots H. The center of this rotative play is thrown above the surface of the lids A B, as indicated by dots in Figs. 1, 2, and 3, for the following reason: The lids A and B are very closely fitted. The edges are very sharp and highly finished; hence if we swing the lid B on a hinge whose center is above the surface of the lid the edge of the lid B will be slightly drawn away from the edge of the lid A, thus preserving the edges of both lids. Fig. 1 shows the position of our improved hinge when lids are closed.

When we raise the lid B, the curved wings D' will play around the coupling-rod E the full length of the slots H. The length of these slots in the curved wings D' is such as to allow the curved wings D' to play around the rod E until the lid B is in a vertical position, as shown in Fig. 2. At this point the curved wings D' will "pick up" the rod E and rotate it within the curved wings C' until the lid B is entirely opened, as shown in Fig. 3. Fig. 5 is a top view showing our improved hinge mortised and fitted to the lids A B.

We do not limit ourselves to the exact construction herein illustrated and described—as, for instance, to the number of the curved wings employed and other details—but reserve the right to make all such minor changes and modifications as may properly fall within the scope of our invention.

Having fully described our invention, what

we claim as new, and desire to secure by Letters Patent, is—

1. The combination, with two substantially counterpart hinge-leaves, each having curved and slotted arms or wings which interlap, as described, of a connecting-rod to which said wings are secured, substantially as described.

2. The combination, with the hinge-leaves having interlapping wings formed with elongated slots, as described, of a connecting-piece nearly semicircular in cross-section, said slotted wings being secured by screws passing through the slots thereof, whereby the wings of one of the leaves have a limited movement upon the connecting-piece and the latter a limited movement within the wings of the other leaf, substantially as described.

3. The combination, with the hinge-leaves, each having curved wings formed with elongated slots, of the approximately semi-cylindrical coupling-rod formed with screw-threaded holes, and the screws F, each formed with collars to bear within the slots of the curved wings, substantially as described. 20

In testimony whereof we have signed this 25 specification in the presence of two subscribing witnesses.

CHARLES FISHER.
GEO. B. BURNET.
